UNITED STATES PATENT OFFICE.

REUBEN J. FINKLE, OF GREAT FALLS, MONTANA.

BUNDLE OR SHEAF LOADER.

1,315,713.

Specification of Letters Patent.

Patented Sept. 9, 1919.

Application filed April 10, 1917. Serial No. 160,998.

To all whom it may concern:

Be it known that I, REUBEN J. FINKLE, a citizen of the United States, residing at Great Falls, in the county of Cascade and State of Montana, have invented certain new and useful Improvements in Bundle or Sheaf Loaders; and I do hereby declare the following to be a full, clear, and exact description of the invention, such as will 5 enable others skilled in the art to which it appertains to make and use the same.

This invention relates to a loading device for bundles or sheaves of grain, and the primary object of the invention is to provide a machine which, upon travel over a field of cut and bound grain, will pick up the bundles or sheaves of grain, deliver them to a combined conveyer and elevator which will in turn elevate the sheaves for deposit 15 into a wagon or analogous receptacle.

Another object of this invention is to provide a pick-up structure, which includes a bottom and upstanding sides which are pivotally connected to the main supporting 25 body of the sheaf loader and which carry rotary pick-up members and a conveyer which receives the bundles from the pick-up fingers and delivers them to the combined conveyer and elevator.

30 A further object of this invention is to provide a pick-up structure including a plurality of rods having radially extending tines of sheaf engaging fingers carried thereby, which travel in a circular path and are operated through the medium of a channeled cam for moving the fingers into a bundle engaging position and during the rotation moving them out of a bundle engaging position so that they will release 35 the bundles for permitting the latter to be carried upwardly by the conveyer structure.

40 A further object of this invention is to provide a gearing structure, for operating the conveyer, by the travel of the bundle loader, which structure is constructed so as to permit of the pivoted movement of the pick-up structure supporting frame without disconnecting the operating mechanism so as to allow the pick-up structure to move 45 independent of the main body of the loader structure when traveling over uneven places in a field.

Another object of this invention is to provide a pivotally mounted guard structure which includes a rock or pivotally 50 mounted shaft having a plurality of ar-

cuate tines carried thereby which tines are curved and extend over the delivery end of the elevator.

With the foregoing and other objects in view, this invention consists in such novel features of construction, combination and arrangement of parts as will be hereinafter more fully described, illustrated in the accompanying drawings, and claimed.

In describing the invention in detail, reference will be had to the accompanying drawings wherein like characters designate like and corresponding parts throughout the several views, and in which:

Fig. 1 is a top plan view of the improved bundle loader;

Fig. 2 is a vertical section on the line 2-2 of Fig. 1;

Fig. 3 is a cross section on the line 3-3 of Fig. 1;

Fig. 4 is a section on the line 4-4 of Fig. 1;

Fig. 5 is an enlarged fragmentary plan of the bundle pick-up mechanism;

Fig. 6 is a section on the line 6-6 of Fig. 5, showing the channeled cam for moving the pick-up fingers into and out of bundle engaging positions;

Fig. 7 is a horizontal section through the machine;

Fig. 8 is a fragmentary elevation of the pick-up or receiving end of the machine;

Fig. 9 is a detail view illustrating one of the sprockets employed for operating the pick-up mechanism; and

Fig. 10 is a perspective view of a guide employed for guiding the travel of the upper run of the combined conveyer and elevator so as to maintain part of the same in a horizontal plane.

Referring more particularly to the drawings, 1 designates the main supporting frame of the bundle loader which is constructed of channel iron or any suitable material and it has a forwardly extending tongue or arm 2 attached to the front end of the same which is braced by suitable braces 3 and has a vertically adjustable swivelly mounted front wheel 4 carried by its forward end.

The frame 1 is provided with a cross brace 5 upon which is mounted a bearing 6. The main axle 7 of the loader is rotatably supported by the bearing 6 and a bearing 8 which is carried by one end of the frame. The shaft 7 has a bull wheel 9 mounted

thereon. A sprocket 10 is also mounted upon the shaft 7 and a sprocket chain 11 travels about the sprocket 10 and about a sprocket 12 which is carried by a shaft 13. The shaft 13 extends longitudinally along the front side of the supporting frame and it has a beveled gear 14 mounted thereon which meshes with a second beveled gear 15. The beveled gear 15 is mounted upon a shaft 16 positioned at one end of the supporting frame 1. The endless belt or canvas 17 of the combined conveyer and elevator structure 18 travels over the roller 16 and the rotation of the shaft 16 by the rotation of the axle 3 provides the necessary power for operating the conveyer and elevator structure.

The belt 17 is of the usual canvas construction having a plurality of flights 19 attached thereto at spaced intervals, and the uppermost end of the belt passes over a roller 20 which is supported at the upper end of the supporting and containing frame work 21 of the elevator structure. The supporting and containing frame work 21 is braced by suitable braces 22 and by its connection with the upstanding guides 23 of the conveyer structure containing means which are suitably attached to the supporting frame 1. Guards 24 and 25 are attached to the inner surface of the upstanding side plates 23 and these guard structures comprise substantially vertical attaching plates 26 which have plates 27 attached to their lower edges and extending outwardly at right angles thereto. The ends of the plates 27 are curved as shown at 28 for properly guiding the horizontal runs of the belt 17 so as to maintain the conveyer portions of the combined conveyer and elevator in a horizontal plane as clearly shown in Fig. 2 of the drawings.

The standards 22 project above the frame 21 and they have a rod 30 pivotally carried thereby, which rod has a plurality of tines or fingers 31 attached thereto and extending outwardly therefrom. The outer ends of the rods 31 are curved as shown at 32 so as to extend over the delivery end of the elevator structure 18 so as to prevent the bundles or sheaves of grain from flying over the edge of the frame work 21, properly guiding the bundles or sheaves to the wagon or retaining receptacle. The rod 30 is mounted so as to allow free unimpeded movement of the fingers 31.

The bundles or sheaves of grain are deposited upon the horizontal portion of the combined conveyer and elevator, by means 60 of the pick-up structure generically indicated by the numeral 40.

The pick-up structure 40 includes a retaining and supporting frame 41, which is pivotally connected through the medium of a shaft 42 to plates 43. The plates 43 are

in turn connected to the supporting structure 1 in any suitable manner and they form bearings for the shaft 13 as well as forming connecting brackets for the structure 41. The shaft 42 has a pair of sprockets 44 mounted thereon, about which the chains 45 of the pick-up conveyer travel. The chains 45 also travel about sprockets 46 which are positioned at the lower outer end of the frame 41.

The sprockets 46 have a plurality of openings 47 formed therein through which shafts 48 extend. The shafts 48 have a plurality of bundle or sheaf engaging fingers 49 attached thereto in spaced relation and extending radially from the shaft as clearly shown in Figs. 5 and 3 of the drawings. The ends of the shafts 48 which extend through the sprockets 46 have rollers 50 positioned upon each side thereof and attached thereto in any suitable manner. The rollers 50 are of substantially equal diameter to the shafts 48 and they, together with the shafts ride in the channels 51 of channelled cams 52 which are secured to the inner surfaces of the sides 41. The channels 51 are provided with enlarged portions 53 which allow the shafts to rotate during their passage about the channels for moving the fingers 49 out of bundles of grain which have been previously engaged by the fingers and picked up for deposit upon the conveyer 45 which elevates the bundles for deposit upon the horizontal conveying portion 17. The enlarged portion 53 is provided with a relatively abrupt shoulder 54 which is designed for making a quick upturn to the path for forcing the fingers 49 into a sheaf or bundle of grain for picking it up by the rotation of the cams 46 and the movement 105 of the shafts 48 and fingers 49 therewith.

The shaft 42 has a gear 56 mounted thereon which meshes with a gear 57 that is carried by the shaft 13 and it is through the medium of these gears 56 and 57 that power 110 is transmitted to the shaft 42 for operating the conveyer structure 45. The provision of the gears 56 and 57 allow for pivotal movement of the pick-up structure 40 independent of the main body portion of the bundle 115 loader without disconnecting the shafts 42 and 13.

Suitable supporting wheels 60 are carried by brackets 61, which brackets are attached to the sides 41 near their outer lower ends 120 and a supporting wheel 62 is mounted upon a supporting axle 63, which axle is attached to the under surface of the frame 1, remote from the bull wheel 9.

During the travel of the improved bundle 125 loader over a field, the travel of the ends of the shafts 48 within the channels 51 of the cams 52 will move the fingers 49 into bundle engaging positions so that these fingers will pick up bundles and carry them upwardly 130

and deposit them upon the conveyer structure 45 which conveyer structure will carry the bundles upwardly and deposit them upon the horizontal conveyer portion 17 5 which will carry the bundles upwardly to the upwardly inclined elevator portion of the combined conveyer and elevator and deliver them from the upper delivery end thereof into any suitable type of wagon or 10 receptacle, as desired.

From the foregoing description taken in connection with the accompanying drawings the advantages of construction and of the method of operation of the improved bundle 15 or sheaf loader, will be readily apparent to those skilled in the art to which this invention appertains and, while in the foregoing description, the principle of the operation of this invention has been described together with various features of construction, 20 it is to be understood that certain minor features of construction, combination and arrangement of parts may be altered to suit practical conditions provided such alterations are comprehended within the scope of 25 what is claimed.

What is claimed is:—

In a bundle loader structure, a supporting

frame, a combined conveyer and elevator carried by said supporting frame and comprising a horizontal conveyer portion and an upwardly inclined elevator portion, an auxiliary supporting structure pivotally connected to said first mentioned supporting structure, a conveyer carried in said auxiliary supporting structure, means for operating said conveyers, and guides carried by said first mentioned supporting frame arranged on each side of the combined conveyer and elevator and including a vertical 40 attaching portion and an inwardly extending horizontal portion having one terminal thereof free and extended beyond the attaching portion and constituting a resilient engaging means, said engaging means being 45 curved upwardly for engaging the upper run of the combined conveyer and elevator for holding the horizontal conveyer portion and inclined elevating portion in their proper positions, as and for the purpose specified. 50

In testimony whereof I affix my signature in presence of two witnesses.

REUBEN J. FINKLE.
